(57) **CLAIM**

The ornamental design for a hip seat carrier as shown.

DESCRIPTION

This application contains related subject matter by a common inventor with the following applications:

- U.S. patent application Ser. No. 14/247,406 titled “Baby Carrier with Removable Seat,” filed Apr. 8, 2014 by Khai Gan Chuah and issued as U.S. Pat. No. 9,314,112;
- U.S. patent application Ser. No. 29/501,398 titled “Booster Seat Baby Carrier,” filed Sep. 3, 2014 by Khai Gan Chuah and issued as U.S. Pat. No. D755,508;
- U.S. patent application Ser. No. 29/693,889 titled “Baby Carrier,” filed Jun. 5, 2019 by Khai Gan Chuah;
- U.S. patent application Ser. No. 29/719,449 titled “Hip Carrier,” filed Jan. 3, 2020 by Khai Gan Chuah; and,
- U.S. patent application Ser. No. 16/854,812 titled “Baby Seat Carrier,” filed Apr. 21, 2020 by Khai Gan Chuah.

FIG. 1 is a front view of a hip seat carrier showing my new design;

FIG. 2 is a rear view thereof;

FIG. 3 is a right perspective view thereof;

FIG. 4 is a left perspective view thereof;

FIG. 5 is a right view thereof;

FIG. 6 is a left view thereof;

FIG. 7 is a top view thereof;

FIG. 8 is a top view of a hip seat carrier according to the present invention, wherein the belt has been detached for convenience of illustration;

FIG. 9 is a bottom view thereof; and,

FIG. 10 is a bottom view of a hip seat carrier according to the present invention, wherein the belt has been detached for convenience of illustration.

The broken lines depict portions of the hip seat carrier that form no part of the claimed design.

1 Claim, 10 Drawing Sheets
